STOCKING

Earl A. Gerhardt, Lynchburg, Va., assignor to Lynchburg Hosiery Mills, Inc., Lynchburg, Va., a corporation of Virginia

Application August 1, 1950, Serial No. 11,512

Term of patent 14 years

(Cl. D47—7)

To all whom it may concern:

Be it known that I, Earl A. Gerhardt, a citizen of the United States, residing at 1304 Edley Place, in the city of Lynchburg and State of Virginia, have invented a new, original, and ornamental Design for a Stocking, of which the following is a specification, reference being had to the accompanying drawings, forming a part of this application, and in which

Fig. 1 is a side elevational view of a stocking, showing my new design; and

Fig. 2 is a perspective view thereof illustrating the sole portion.

I claim:

The ornamental design for a stocking, as shown.
EARL A. GERHARDT.
